UNITED STATES PATENT OFFICE.

ANGELO F. GARBERDING, OF GOODLAND, MINNESOTA.

BELT.

1,421,451.

Specification of Letters Patent.

Patented July 4, 1922.

Application filed March 21, 1921. Serial No. 454,085.

To all whom it may concern:

Be it known that I, ANGELO F. GARBERDING, a citizen of the United States, residing at Goodland, in the county of Itasca and 5 State of Minnesota, have invented new and useful Improvements in Belts, of which the following is a specification.

My invention relates, in general terms, to improvements in cartridge belts, and more 10 particularly it has reference to the provision of a reinforcing and protecting strip for the belt which also serves as a receptacle for money and the like.

The principal object of my invention is 15 to provide a cartridge belt for either small arms or shot gun ammunition, wherein certain adjustments may be effected to adapt the belt for use in carrying a variety of sizes or calibres of cartridges, and further- 20 more the cartridge carrying means of my belt, when adapted for the reception of cartridges of small calibre, may be adjusted so that the belt in its entirety may be used either as a waist belt or money belt.

25 Another and equally important object of my invention is to provide a reinforcing and protecting strip for the belt, a portion of which is open for the reception of money and the like, and a portion of which is closed 30 to form a safety pocket for the reception of change and the like.

A further object of my invention is to 35 provide a combination cartridge and money belt the body of which is constructed of but three strips of leather which are so associated together that a compact and comfortable belt is afforded which is extremely durable, and which may be placed upon the market at a comparatively small retail price.

40 To these and other ends, my invention consists in the construction, arrangement and combination of parts described herein- after and pointed out in the claims forming a part of this specification.

45 One embodiment of my invention is represented by way of example in the accompanying drawings, wherein:

Figure 1, is a view of the front portion of my belt showing to advantage the arrangement of the cartridge carrying member thereof.

50 Figure 2, is a view of the reverse or back portion of my belt showing the position of the combination reinforcing strip and 55 pocket, and partially broken away to show its relation to the cartridge strip.

Figure 3, is an edge view of my belt broken away to show the manner of forming the cartridge compartments, and

Figure 4, is a detail view taken on the 60 line 4—4 of Figure 1.

Like characters of reference refer to like or similar parts throughout the several views of the drawings, in which:

The numeral (1) designates the body of 65 my belt which in the present instance is in the form of a single strip of leather having a conventional buckle (2) attached in the usual manner to one end thereof, and pro- 70 vided with a series of perforations (3) in the other end to receive the tongue of the buckle. The body of the belt between the buckle (2) and the perforations (3) is formed with a plurality of uniformly 75 spaced apart, parallel pairs of transverse slits (4) through which a strip of material (5), such as leather, is trained (see Figure 3). The strip (5) is attached at one end to the body of the belt adjacent the buckle thereof, and a second buckle (6) is secured 80 to the belt adjacent the perforations (3) therein for receiving the other end of the strip. When the belt is to be used as a waist belt the strip (5) is drawn substantially flat against the body, but when the belt is to be 85 used as a cartridge belt the portions of the strip between the pairs of slits (4) are curved 90 outwardly as in Figures 2 and 4 to form compartments in which the cartridges (not shown) are inserted. As the strip is adjustable through the instrumentality of the buckle (6) various sizes of cartridges may be carried.

Mounted upon the rear portion of the belt and directly back of the strip (5) is a re- 95 inforcing strip (7) which is sewn or otherwise secured to the body along one of its edges and around its ends as in Figure 2, thereby preventing the body of the belt from contacting with the body of the 100 wearer. Furthermore, the reinforcing strip (7) is sewn or otherwise attached to the body along only a portion of its remaining edge so that an open pocket (8) and a closed 105 pocket (9) are provided to receive money or the like.

The buckle (6) is attached to the belt body by inserting the tongue thereof through a pair of slits (10) formed in the body so that it may be readily removed 110 when so desired and the free end of the strip (5) is inserted through a pair of slits (11).

in the body which form in effect a suitable receiver therefor.

Attention is particularly directed to the fact that the reinforcing strip (7) serves 5 also as a pocket, and that only three strips of material, such as leather, are used in its construction. Furthermore, it is also pointed out that not only is the cartridge carrying feature of the belt capable of a 10 wide range of adjustment, but it may be rendered substantially passive by tightening the strip (5) so that the belt may be used either as a waist belt or a money belt.

While in the foregoing, there has been 15 illustrated and described such combination and arrangement of elements as constitute the preferred embodiment of my invention, it is nevertheless desired to emphasize the fact that interpretation of the invention 20 should only be conclusive when made in the light of the subjoined claims.

Having described my invention and its objects with such attention to detail as will thoroughly acquaint one skilled in the art 25 with its construction and advantages, I claim—

1. A belt comprising a body portion formed with a plurality of transverse pairs of uniformly spaced apart slits and a pair 30 of slits spaced from the first mentioned uniform slits, said body portion further provided with a pair of relatively short slits disposed between the first and second mentioned slits, a buckle disposed with its 35 tongue through the last named slits, and a strip of material trained through the first mentioned slits and held in position by the buckle with its free end trained through the second mentioned slits which serve as 40 a keeper therefor.

2. A belt comprising a body portion having a plurality of transverse slits formed therein, an adjustable elongated strip of material attached to the belt and trained through said slits to form cartridge receiving compartments, and an elongated strip of material secured along three edges and part of its fourth edge to the body of the belt to reinforce the same and to provide pockets for the reception of money and the like. 45

3. A combination cartridge and money belt formed of three strips of material, one strip of material forming the body and provided with slits, another strip trained through the slits to form cartridge receiving compartments, and the remaining strip attached to the body to reinforce the same and provide pockets for receiving money and the like. 55

4. A combination cartridge and money belt comprising a body portion formed of a single strip of material and provided with a plurality of spaced apart, transverse pairs of slits, a single strip of material attached 65 at one end to the body of the belt and trained through the pairs of slits to form cartridge receiving compartments, a buckle removably attached to the body portion for adjustably retaining the last mentioned 70 strip of material, and a strip of material attached along three of its edges and part of its fourth edge to the rear portion of the body to reinforce the same and to provide pockets adapted for the reception of 75 money and the like.

In testimony whereof, I affix my signature hereto.

ANGELO F. GARBERDING.
